UNITED STATES PATENT OFFICE.

RAY BONEBRAKE, OF SOUTH WHITLEY, INDIANA.

ELECTRICAL SAFETY TRIP.

Application filed September 8, 1927. Serial No. 218,334.

My invention relates to an electrical safety trip mechanism and the same has a more particular reference to a safety trip for use in conjunction with book binding machines.

5 This mechanism is particularly adapted for installation on certain types of machines, wherein the book sections pass through the process of gathering, stitching, gluing and covering stages.

10 Not only in this type of machine, but in all types of book binding machines, considerable difficulty has been experienced in the irregular carrying of the book section upon the various conveyors. In the production of large catalogues and other magazines, the same are constructed of a group of sections, each section comprising a uniform number of pages.

These sections are usually placed upon 20 a platform provided for the purpose, and in turn are caught by a gripper arm and placed upon an endless conveyor for movement toward the stitcher. In this line of travel, the book sections frequently have their end 25 portions, or corners, curled against the side walls of the conveyor. In this condition, the book sections pass onto the stitcher where they are stitched in their defective condition.

30 Not only are books produced in this manner with defective sections, but not infrequently, serious damage is done to various parts of the book binding machine.

An object of my safety trip mechanism 35 is to entirely eliminate any possibility that these defective sections will find their way into finished catalogued magazines, the main purpose being to remedy this situation immediately upon its occurrence.

40 Another object is in having my safety trip mechanism fool-proof, in that the book sections are compressed by a presser bar prior to their passage under my trip device.

Still another object resides in the novel 45 arrangement and construction of parts I have provided for instantaneously breaking the electrical circuit and stopping the machine.

A further object lies in the convenient 50 way in which this mechanism may be applied to any part of an endless conveyor, requiring but a minimum of space and necessitating but little labor and time.

Other objects and advantages will become apparent as the novel construction of my invention is better understood from the specification and claims to follow.

In the drawing:

Figure 1 is a front elevation of my electrical trip mechanism showing the same applied to the side wall of an endless conveyor, the same further showing book sections on the endless conveyor and the presser bar of my mechanism in contact with one of the book section.

Fig. 2 is a sectional view through the circuit breaker housing of my mechanism, showing the contact of the breaker in closed position, and

Fig. 3 is a perspective view of the construction as shown in Fig. 1.

For a more detailed description of my invention, I will now refer to the drawings, in which like numerals designate like parts of my invention.

An endless conveyor or other conveying means 1 of conventional construction, is employed upon which is conveyed the same book sections A to the stitcher, gluer and covering operations of the bookbinding machine.

This endless conveyor is also provided with a side wall 2 which is shown in Fig. 3, and on which my electrical trip mechanism is mounted. Letter B represents a plate of suitable shape having elongated ribs 3 and 4 respectively, extending longitudinally from the lower edge of the plate for a substantial distance.

The plate is further formed with longitudinal slots 5 and 6 and 7 respectively. A lug 8 projecting outwardly, is also provided on the face of the plate adjacent one side edge and intermediate the length of same. A rocker arm 9 having the lower portion thereof of a curved contour, is adapted to pivot on a threaded pin 10. The threaded pin 10 is provided with a suitable nut threaded thereon at the opposite side of the plate B, which is not shown in the drawing, and the same is adapted for slidable adjustment within the slot 7.

The curved portion of this arm adjusted below the pivot pin, is adapted to abut the rib 4 on the plate, to limit the downward movement of the trip plate 11 formed at the

lower extremity of the arm. The upper extremity of the arm is formed with an internally threaded opening, through which is threaded an adjusting screw 12 provided with a suitable cam nut 13 for receiving the adjusting screw in a desired position.

Pivoted adjacent the top of the plate 13 is a lever 14 formed with an enlarged head portion 15 in which is located an arcuate-shaped slot 16. Freely movable within this slot 16 is a pin from which depends the rod 17. When the trip mechanism is in set position, the lower extremity of this rod 17 is adapted to rest on the lug 8, in close proximity to the extremity of the adjusting screw 12.

Extending beyond the pivot point of lever 14 is a finger 18 formed at its free end portion with an outward bend. Bar section 19 pivoted at 20 to the lower part of the plate, is formed with a yoke head 21. Pivoted in this yoke is a link bar 22 which pivotally connects the bar section 19, the switch plunger 23. The switch plunger is internally threaded at its opposite end into which an adjusting screw 24 provided with a suitable jamb nut 25 is threaded. An insulating block 26 carried on the adjusting screw 24 supports the spring leaf 27, the opposite extremities of which carry contact members 28.

At the top of the plate B is provided a suitable base 29 for supporting the switch housing 30. This switch housing may be of any desired shape, in which is located at the top inner side, an insulating plate 31, secured in a suitable manner. Carried by this insulating plate 31, are a pair of contact blocks 32 in direct overlying position with contact blocks 28.

Suitable conductor wires 33 are connected with the proper electrical motive power of the machine. The presser bar 34 formed at one end with a suitable plate 35 is adapted for adjustment within the slot 5. The pin 36 upon which the presser bar is allowed to pivot is provided with a spring 37 for normally maintaining the presser plate 35 in tensioned relation with the book section A as a pass thereunder, upon the conveyor 1.

Threaded bolts extend through the side wall 2 of the conveyor and through the slot 6 in plate B and are provided with nuts 38 adapted to be tightened against the plates for securing same in proper position on the wall.

In use, my trip mechanism is secured to the side wall 2 of the conveyor and is adjusted in proper position thereto through the slot 6 formed in the plate. Presser bar 34 is then adjusted properly so that the plate 35 will effectively compress successive book sections as they pass thereunder.

Frequently, these book sections are inflated or bulky and then must be compressed before they are allowed to pass under the

trip plate 11. However, due to the edges of these book sections becoming curled as shown in Fig. 3, the same will engage the trip plate 11 to cause the same to pivot on the pin 10.

When this movement takes place, the adjusting screw 12 will move towards the lower extremity of bar 17 to cause the same to become displaced from support on the lug 8. As this occurs, the lever 14, which is of weighted construction, will swing downwardly causing the outwardly curved free end of finger 18 to engage the yoke portion of bar 19.

A slight engagement will cause this joint to break, allowing plunger 23 to drop and in turn separating the contact blocks 28 from the contact 32. This instantly breaks the circuit, causing the endless conveyor to stop, and allow the proper remedy for correcting the defective situation. The rib 3 serves to align the arm and link section while my mechanism is in set position.

Proper adjustment of adjusting screw 24 and jamb nut 25 may be made, for effecting the proper tension of the leaf springs 27 with respect to the contact blocks.

Having thus described my invention, what I claim as new is:

1. In a trip mechanism for breaking an electrical circuit to the motive means actuating an endless conveyor, a trip arm adapted to be actuated by the passage of an object on the conveyor, the weighted bar associated with the plate and adapted to be released by the movement of the trip arm, a linked bar normally having its sections aligned, said linked bar adapted to be displaced from alignment by the movement of the weighted bar.

2. In a trip mechanism for breaking an electrical circuit comprising a plate, a trip arm, an abutment on the plate for engaging the end of the trip arm, a linked bar having the sections thereof normally in alignment, said linked sections adapted to be displaced by the movement of the trip arm, an abutting rib on the plate for maintaining the linked bar section normally in alignment when the mechanism is in set position, a platform mounted at the top of the plate, a switch means arranged thereon and in operative connection with the linked bar.

3. In a trip mechanism for breaking an electrical circuit comprising a plate, a trip arm, an abutment on the plate for engaging the end of the trip arm, a linked bar having the sections thereof normally in alignment, said linked sections adapted to be displaced by the movement of the trip arm, an abutting rib on the plate for maintaining the linked bar section normally in alignment when the mechanism is in set position, a platform mounted at the top of the plate, a switch means arranged thereon and in opera-

tive connection with the linked bar, said switch means comprising a fixed contact block, a plunger adapted to be moved by said linked bar, and adjusting screw threaded 5 into one end of said plunger, a movable contact block carried by said screw and adapted to be adjusted in respect to the fixed contact, and resilient means interposed between the movable contact block and the 10 fixed contact block.

4. In a trip mechanism for breaking an electrical circuit comprising a plate, a trip arm, an abutment on the plate for engaging the movement of the trip arm, a linked bar 15 having the sections thereof normally in alignment, said linked sections adapted to be displaced by the movement of the trip arm, an abutting rib on the plate for maintaining the linked bar section normally in alignment 20 when the mechanism is in set position, a platform mounted at the top of the plate, a housing arranged upon said platform, a fixed contact block carried on the inner side of the top of the housing, a plunger connected 25 at one end and with the linked bar, an ad-

justing screw threaded in the opposite end of the plunger, the movable contact carried by the adjusting screw, and resilient means interposed between the movable contact and the fixed contact.

5. In a trip mechanism for breaking an electrical circuit comprising a plate, a trip arm, an abutment on the plate for engaging the movement of the trip arm, a linked bar having the sections thereof normally in alignment with said link sections adapted to be displaced by the movement of the trip arm, an abutting rib on the plate for maintaining the linked bar section normally in alignment when the mechanism is in set position, a platform mounted on the top of the plate, a pair of fixed contact blocks supported over the platform, a plunger operative through said platform, a leaf spring supported on said plunger, and a pair of movable contact 40 blocks secured at opposite ends of the spring, and in direct underlying position with respect to the fixed contact block.

In testimony whereof I affix my signature.
RAY BONEBRAKE.
